UNITED STATES PATENT OFFICE.

SAMUEL BROWN, OF ST. LOUIS, MISSOURI.

GUMMED-TAPE-MOISTENING MACHINE.

1,111,434.

Specification of Letters Patent. Patented Sept. 22, 1914.

Application filed May 29, 1913. Serial No. 770,725.

To all whom it may concern:

Be it known that I, SAMUEL BROWN, citizen of the United States, residing at St. Louis, State of Missouri, have invented certain new and useful Improvements in Gummed-Tape-Moistening Machines, of which the following is a full, clear, and exact description; reference being had to the accompanying drawings, forming a part hereof.

My invention has relation to improvements in gummed-tape-moistening machines; and it consists in the novel details of construction more fully set forth in the specification and pointed out in the claims.

In the drawings, Figure 1 is a top plan of the machine; Fig. 2 is a vertical longitudinal section on the zig-zag line 2—2 of Fig. 1; Fig. 3 is a front end elevation of the same; and Fig. 4 is a vertical cross-section on the line 4—4 of Fig. 2.

The present invention is directed to machines in which strips of paper gummed on one side are automatically moistened with the withdrawal of the paper from the machine, the paper being usually in the form of a roll mounted on a reel from which any length of strip may be torn off; such moistened strips being used for the sealing of packages and bundles in commercial houses, as well understood in the art. In the class of machines here referred to, it is usual to moisten the gummed side or face of the paper strip to cause the same to quickly adhere to any surface to which it may be applied.

In the present embodiment of my invention the object sought is to moisten both sides of the gummed strips, a moistening from both sides overcoming many objections inherent in the prevailing practice of moistening the gummed side only. In the first place it is usual to draw the paper across a cutter or knife to sever the same when the proper length has been drawn from the reel; a section of the moistened paper usually remaining unsevered. Being moistened on one side only it tends to curl, thus leaving a curled terminal for the succeeding section to be severed, such curled portion being usually wasted, the clerk tearing it off and throwing it away. By moistening the strip on both sides no curling or warping is possible. Again, by moistening both sides, the body of the strip becomes impregnated with water to such an extent that when the strip

eventually dries on the package about which it may have been wrapped, the strip undergoes a maximum shrinkage so that it hugs the package and insures therefor a close fitting wrapper. Where, as in the present case the paper is used for wrapping and sealing corrugated boxes, the moistening from both sides makes the paper exceedingly pliable which is eminently desirable where serving the purpose of a wrapper for boxes of this character. The machine herein too, is provided with means which prevent the terminal of the main body of the tape from which the wrapping and sealing strip was severed, adhering to the moistening drum or cylinder, the machine being provided with further and other details of construction the advantages of which will be more fully apparent from a detailed description of the invention which is as follows:

Referring to the drawings, 1, 1, represent the side basal members of a suitable supporting frame, the same being connected by tie-rods *t*, *t*, and provided with standards 2, 2, for the support of the spindle 3 by which the paper roll is supported. The sides 1, 1, are provided with lugs *a*, *a*, spaced apart to receive a bolt (not shown) by which the frame may be secured to a counter, table, or other suitable support. The ends of the spindle 3 rest in depressions or recesses *b* formed in the standards 2, the terminals of the spindle being screw-threaded to receive nuts 4, which can be screwed more or less firmly against the bosses *c* of the heads 5, 5, passed loosely over the spindle 3, the heads 5, 5, being preferably composed of a series of arms radiating from the hub or boss *c* as shown, to lighten the same, and serving to guide the roll of tape *h* mounted on the spindle between them, it being understood that the tape is gummed on the underside or the side facing the members 1, 1, as it is pulled off the roll. At the forward end of the frame is a basin or tank 6 holding water, between the sides of which is mounted a peripherally grooved drum or cylinder 7 dipped beneath the surface of the water (Fig. 2), the grooves *m* running longitudinally as shown, and serving to gather or pick up the water with the turning of the drum. The latter is provided with trunnions 8, 8, resting in bearings 9, on the sides of the tank. Spanning the drum 7 and disposed to one side and rearward of, the

axis of rotation thereof is a U-shaped frame 10, the sides of the frame being secured in any mechanical manner to the inner faces of the side walls of the tank 6, the upper 5 horizontal member of said frame having secured thereto and on the under side thereof, a preferably serrated cutting blade or knife 11 or equivalent cutter.

At the rear of the tank 6 and between 10 the portions of the side walls thereof which overhang the front portion of the space between the members 1, 1, is secured in any mechanical manner a water trough or container 12 whose end and rear walls are 15 spanned by a wire or equivalent U-shaped rail or frame 13, the medial portion of the rail being spaced from the rear wall of the trough. Said portion of the rail serves to lock the heads 5, 5, against possible rotation 20 with the unrolling of the tape from the spindle 3, a pair of arms of the respective heads being provided with terminal notches or recesses *n* to engage the rail (Fig. 2) the latter thus serving to lock the heads 25 against rotation. In practice, the notches *n* are made to engage the rail as the spindle 3 (with the heads 5, 5, thereon) is being deposited into its supporting recesses or depressions *b*.

30 The trough 12 is preferably soldered or secured to the walls of the tank 6 through the medium of the brackets 12' formed with the trough, there being disposed between the said brackets a guide rod 14 spaced from the 35 bottom of the trough sufficiently to allow for the passage of the tape between the trough and rod (Fig. 2). The bottom of the front wall of the trough 12 is provided with a series of discharge openings *o* or their equivalents opposite which there is secured in the outside of the said wall a strip or layer of felt or equivalent brush 15, said felt projecting a suitable distance below the bottom of the trough, the edge of the felt being thus 40 positioned to engage the upper face of the tape. The felt is preferably secured in position by an angle-bar 16 screwed to the wall of the trough. Disposed between the trough 12 and the drum 7 and supported between 45 the sides of the tank 6 is a bar 17 to which is screwed or otherwise secured one edge of an apron 18 bent trough-shaped, there being disposed immediately over the trough or bend of the apron a rod 19 secured between 50 the sides of the tank 6, said rod serving to guide the tape in its passage over the forward portion of the apron as shown (Fig. 2). The apron is spaced from the drum 7, its front edge terminating in a rearwardly 55 bent lip *d* which serves to hold the projecting end of the tape (after the desired length has been severed by the cutter 11) from contact with the moistened drum, and hence preventing the premature moistening of the 60 gummed side of the tape. The members 19,

17, 10, 14, are all disposed parallel to the axis of the drum 7, which is itself parallel to the axis of the spindle 3.

The operation of the device may be described as follows:—A roll of tape *h* of convenient size being mounted loosely on the spindle 3, and the heads 5, 5, being applied to the spindle, the latter is deposited in its recesses *b*, and the free end of the tape (which is gummed on its under side) is 70 passed as shown in Fig. 2, between the trough 12 and rod 14, then over the rear of the guide apron 18 directly above the bar 17, then between the apron and the rod 19, then over the lip *d* and over the periphery of the 80 drum 7. A draft on the tape will necessarily rotate the drum 7 as well as the roll on the spindle 3. The water in the trough 12 will keep the felt 15 moistened, the felt in turn moistening the upper or ungummed side of 85 the tape, said upper side being thus moistened slightly in advance of the bottom or gummed side which latter is not moistened until it passes over the drum 7, the grooves *m* thereof mechanically carrying the water 90 in sufficient quantities to moisten the tape on the bottom. Thus both sides of the tape become moistened, the moisture impregnating the same and rendering the tape pliable; and being moistened on both sides it 95 does not curl when the piece severed by the knife is removed for application to a box, package or parcel which is to be wrapped or sealed. A sufficient length of the tape being moistened, the same is brought up against 100 the blade 11 and cut off in the usual manner. A rapid withdrawal of the tape would necessarily impart a rapid rotation to the roll on the spindle 3, and to prevent the rotation from continuing under the momentum of the roll after the draft on the 105 tape has ceased, is the object of the nuts 4, 4; for it is obvious that the nuts may be driven against the bosses *e* with sufficient friction to insure the stoppage of the roll once the 110 draft on the tape has ceased. Otherwise, the danger of the roll continuing in its rotation and the consequent unwinding of an undesired length of tape would be imminent.

The presence of the lip *d* insures a proper 115 deflection of that portion of the tape left projecting between the knife 11 and the lip, after a portion has been severed by the knife, to prevent such projecting portion from adhering to the drum, and hence 120 preventing premature moistening of the gummed side of the tape, or before it is needed. The rod 19 acts as a wiper in that it wipes any excess of water left on the tape or web by the belt or equivalent brush 15. 125 The felt may be renewed from time to time as it wears away by simply removing the strip 16. By moistening the upper or ungummed side of the tape in advance of the 130 gummed side, the interposition of the guide

and wiper member 19 is made possible, from a structural standpoint, it being desirable that no free water should be on the un-gummed side when a strip of the tape is being applied to a parcel intended to be wrapped or sealed.

I do not of course, wish to be limited to the precise structural details here shown.

By "tape" I do not wish to be limited to any particular width of paper or other material, the expression contemplating any sheet supplied from any source (a roll or otherwise) and gummed on one or both sides, or impregnated with adhesive or not 15 gummed at all; neither do I wish to be limited to any length of sheet treated.

Having described my invention, what I claim is:-

1. In a machine of the character described, a rotatable drum, means for supplying water to the peripheral surface of the drum, a source of supply of sheet material, a stationary apron contiguous to the drum and spaced therefrom, means for guiding the sheet over said apron, a cutter for severing the sheet, and a formation on the apron directed away from the drum for normally holding the section of the sheet beyond the apron out of contact with the drum to prevent premature moistening of the sheet.

2. A gummed-tape moistener comprising a suitable frame, a roll of tape mounted at one end thereof, a water tank at the opposite end, a peripherally grooved drum mounted in the tank, an apron bent trough-shaped secured in the rear of the drum and spaced therefrom and provided with a front rearwardly deflected lip, a guide rod above the trough formed in the apron, a water container mounted between the apron and roll and provided with discharge openings, a felt or equivalent strip mounted opposite the openings and having a section exposed 45 to the upper side of the tape, a guide rod below the container over which the tape is

passed before passing under the guide rod and over the apron, and a knife above the drum for severing the tape into any desired lengths.

3. In a tape moistener, a suitable frame, a spindle on said frame for supporting a tape roll, guide-heads on said spindle bearing against opposite ends of the roll, said guide-heads comprising a series of radial arms, a water trough for moistening one side of the tape, means for moistening the opposite side of the tape, a rail carried by the trough on the side facing the spindle, the arms of the guide-heads being provided with notches for engaging the rail whereby the heads are locked against rotation.

4. In a machine of the character described, a moistening member, a source of supply of sheet material, a stationary apron contiguous to the moistening member, means for guiding the sheet over the apron, a cutter for severing the sheet, and a fixed formation on the apron deflected away from the drum and spaced from the guiding means for normally holding the section of the material between the apron and cutter out of contact with the moistening member.

5. In a machine of the character described, a moistening member, a source of supply of sheet material, an apron contiguous to the moistening member and spaced therefrom, means for directing the sheet over the apron, a cutter for severing the sheet, and a terminal fixed formation on the apron tending away from the moistening member and spaced from the directing means for normally holding the section of the material between the apron and cutter out of contact with the moistening member.

In testimony whereof I affix my signature, in presence of two witnesses.
